(57) **CLAIM**

The ornamental design for a remote speaker microphone, as shown and described.

DESCRIPTION

FIG. 1 is a front elevational view of a remote speaker microphone showing our new design;

FIG. 2 is a bottom plan view thereof;

FIG. 3 is a left elevational view thereof;

FIG. 4 is a right elevational view thereof;

FIG. 5 is a rear elevational view thereof;

FIG. 6 is a top plan view thereof; and,

FIG. 7 is an isometric view thereof.

The broken lines shown in FIGS. 1-7 are included for the purpose of illustrating environmental elements only and form no part of the claimed design.
